UNITED STATES PATENT OFFICE.

RAY C. NEWHOUSE, OF CHICAGO, ILLINOIS, ASSIGNOR TO ALLIS-CHALMERS MANUFACTURING COMPANY, OF MILWAUKEE, WISCONSIN, A CORPORATION OF DELAWARE.

CRUSHER.

Application filed April 24, 1926. Serial No. 104,299.

This invention relates in general to improvements in the art of operating vibratory mechanisms and of preventing transmission of vibration from such mechanisms to stationary supporting structure, and relates more specifically to an improved method of and means for eliminating undesirable vibration in machines such as gyratory crushers operable at high speed by means of unbalanced revolving weights or the like.

An object of the invention is to provide an improved method of eliminating transmission or undesirable vibrations to the supports of vibratory machines. Another object of the invention is to provide a method of operating several crushers or the like which are normally operable by centrifugal force induced by revolving eccentric weights traveling at high speed, and utilizing the unbalanced characteristics of the operating weight of one of the crushers to counterbalance that of another without interfering with the efficiency of operation. A further object of the invention is to provide improved apparatus and means for effecting commercial exploitation of the improved method.

A clear conception of an embodiment of the invention and of the mode of effecting commercial exploitation of the improved method, may be had by referring to the drawing accompanying and forming a part of this specification in which like reference characters designate the same or similar parts in the various views.

Fig. 1 is a central vertical section through a high speed gyratory crusher of the type to which the present invention is especially applicable, this machine being substantially the same as shown and described in Patent No. 1,553,333, granted September 15, 1925.

Fig. 2 is a side elevation of a group of high speed gyratory crushers of the general type illustrated in Fig. 1.

Fig. 3 is a top view of the group of high speed gyratory crushers shown in elevation in Fig. 2.

The gyratory crusher specifically illustrated in Fig. 1, comprises a stationary concave 15 cooperable with a gyratory head 16 to provide an annular upright crushing chamber 17, and means for rapidly gyrating

the head 16 within the concave 15. The concave 15 is mounted directly upon a supporting plate 31 and the head 16 is supported by an upright hollow shaft 18 which is carried by a universal suspension bearing 20 associated with a spider 19 mounted upon the concave 15. The crushing chamber 17 has an upper feed inlet 27 and a lower discharge 28, the material being fed through the chamber 17 by gravity. The head suspension shaft 18 is formed hollow to receive an actuator shaft 22, the shaft 22 having its upper end attached to a motor shaft 24 by means of a universal joint 26, and having a revoluble actuator 21 secured to the lower end thereof. The actuator 21 which constitutes the means for rapidly gyrating the head 16, is supported against lateral movement within the head 16 by means of ball bearings 29 and has one or more unbalanced weights 23 secured thereto eccentrically of the shaft 22. The motor shaft 24 is direct connected through a flexible coupling with the driving motor 25 located upon an auxiliary frame carried by the spider 19.

As illustrated in Figs. 2 and 3, there is a group of four high speed gyratory crushers, 3, 4, 5, 6 of the type illustrated in Fig. 1, carried by a common base or supporting plate 31. A common driving motor 2 supported centrally of the group upon a gear casing 30 which is in turn carried by the spiders 19 of the crushers, serves to simultaneously drive all of the crushers. The shaft of the motor 2 carries a pinion 7 which meshes with oppositely disposed transmission gears 8 which in turn mesh with the pinions 10 associated with the actuator shafts of the diagonally opposed crushers 4, 6, and also mesh with idler gears 9. The idler gears 9 mesh with the pinions 11 associated with the actuator shafts of the other set of diagonally opposed crushers 3, 5. With this arrangement of gearing, the single motor driven pinion 7 simultaneously rotates all of the crusher actuator shafts at the same speed and in the directions indicated by the arrows in Fig. 3. The eccentric weights 12, 13 of the opposed sets of crushers 4, 6 and 3, 5 respectively, are so positioned that the resultant centrifugal forces acting thereon will always be equal and opposed, thereby causing the unbalanced

forces tending to vibrate one machine to be maintained equal and opposed to unbalanced forces tending to vibrate another machine, as will be later explained.

5 During normal operation of the group of crushers illustrated in Figs. 2 and 3, the motor 2 is operating to constantly rotate the pinion 7 in a predetermined direction. The rotation of the pinion 7 is transmitted 10 to the gears 8 and from the gears 8 directly to the pinions 10 of the crushers 4, 6 causing the actuator weights 12 of these crushers to revolve in the same direction. The revolving gears 8 produce rotation of the 15 gears 9 which in turn cause the gears 11 and actuator weights 13 of the crushers 3, 5 to revolve in the same direction, but in a direction opposite to that of the weights 12. By properly positioning the weights 12, 20 13 which actuate the several sets of crushers 3, 5 and 4, 6, and maintaining the phase relation, the unbalanced forces tending to produce vibration of the individual crushers may be effectively counter-balanced so that 25 no vibration is noticeable at the supporting plate 31. While the crushers of Figs. 2 and 3 are operable by a common motor 2 transmitting motion to the several crushers through transmission gearing, it will be apparent 30 that the same result may be accomplished by utilizing an independent motor 25 for each machine as illustrated in Fig. 1, and maintaining the proper phase relation between the several motors of a group, electrically. It will also be apparent that the 35 counter-balancing effect is obtainable in groups of three or more crushers or similar machines. The counter-balancing is dependent entirely upon proper relative positioning of the actuator weights of the several crushers and vibration will be eliminated if the weights are so disposed that the resultant forces are maintained equal and opposite at all times.

45 It should be understood that it is not desired to limit the invention to the exact details of construction and operation herein shown and described, for various modifications within the scope of the claims may occur to persons skilled in the art.

50 It is claimed and desired to secure by Letters Patent:

1. The method of eliminating vibration in machines wherein operation is effected by 55 centrifugal force acting upon unbalanced revolving weights, which comprises, causing the actuating weights to travel so that an unbalanced force tending to vibrate one machine is always equal and opposed to a force tending to vibrate another machine.

60 2. The method of eliminating vibration in crushers wherein operation is effected by rapidly revolving eccentric weights, which comprises, causing the actuating weights to travel so that an unbalanced resultant force

tending to vibrate one crusher is always equal and opposed to a resultant force tending to vibrate another crusher.

3. The method of eliminating lateral vibration in gyratory crushers wherein rapid 70 ly revolving weights tend to produce vibration, which comprises, causing the weights to travel so that an unbalanced force tending to vibrate one crusher is always equal and opposed to a force tending to vibrate 75 another crusher.

4. The method of eliminating vibration in a group of gyratory crushers operable from a common source and wherein operation is effected by simultaneously revolving eccentric weights, which comprises, causing the actuating weights to travel in phase so that an unbalanced resultant force tending to vibrate one crusher of the group is always 80 equal and directly opposed to an unbalanced resulting force tending to vibrate another crusher of the group.

5. The method of eliminating vibration in a group of crushers operable by revolving eccentric weights, which comprises, 85 causing the actuating weights to travel in phase so that the resultant forces tending to produce vibration are always balanced.

6. The method of eliminating vibration in a group of crushers operable by rapidly revolving eccentric weights, which comprises, causing the several actuating weights to maintain a definite phase relation during their simultaneous revolution so that the forces tending to vibrate the group are 90 always balanced.

7. In combination, a plurality of crushers each of which is operable by a revolving eccentric weight, and means for moving 95 said weights in definite phase relation.

8. In combination, a group of independently functioning gyratory crushers each having a head gyratable by a revolving eccentric weight, and means for moving said weights so that the vibrations created by one weight are balanced by those created by another.

9. In combination, a plurality of crushers each having a crushing member gyrotable at high speed, and means for causing the vibrations induced in one of said crushers to counter-balance those induced in another.

10. In combination, a plurality of crushers each having a crushing member gyrotable at high speed, common means for driving said crushers, and means cooperating with said driving means and with said crushers for causing the vibrations of one crusher to counter-balance those of another.

11. In combination, a group of independently functioning machines each of which is operable by an unbalanced revolving weight, and means for moving said weights so that unbalanced forces tending to vi-

brate each machine are always counter-balanced by forces tending to vibrate other of said machines.

12. The method of eliminating vibration in a group of machines wherein operation of each machine is effected by centrifugal force acting upon an unbalanced revolving weight, which comprises, causing the

actuating weights to travel so that the unbalanced forces tending to vibrate the individual machines are always counter-balanced by other forces which tend to vibrate other machines of the group. 10

In testimony whereof, the signature of the inventor is affixed hereto.

RAY C. NEWHOUSE.
